(57) **CLAIM**

The ornamental design for a liquid container, as shown and described.

DESCRIPTION

FIG. 1 is a top, front perspective view of a liquid container showing the design, the slightly angled vertical slots extending all the way through the sidewall;

FIG. 2 is a front elevational view thereof; the rear elevational view being identical;

FIG. 3 is a left side elevational view thereof, the right side elevational view being identical; and,

FIG. 4 is a top plan view thereof.
